UNITED STATES PATENT OFFICE.

EDWARD S. MARSHALL, OF ST. LOUIS, MISSOURI, ASSIGNOR TO THE
MISSOURI RAILWAY EQUIPMENT COMPANY, OF SAME PLACE.

DESIGN FOR A CAR-DOOR TRACK.

SPECIFICATION forming part of Design No. 28,742, dated May 31, 1898.

Application filed April 4, 1898. Serial No. 676,466. Term of patent 14 years.

To all whom it may concern:

Be it known that I, EDWARD S. MARSHALL, a citizen of the United States, residing at the city of St. Louis, State of Missouri, have invented a certain new and original Design for Car-Door Tracks, of which the following is a full, clear, and exact description, such as will enable others skilled in the art to which it appertains to make and use the same, reference being had to the accompanying drawings, forming part of this specification, in which—

Figure 1 is a perspective view of a car-door track shaped and configured according to my new and original design. Fig. 2 is a cross-sectional view of the same somewhat enlarged, and Fig. 3 is a side elevational view of the same.

This invention relates to a new and original design for a car-door track; and it consists in the shape and configuration of the same, as will hereinafter be described, and afterward pointed out in the claim.

The essential feature of this new and original design consists in the parallel ribs on the upper face of the horizontal member of the track.

In the drawings, A indicates the vertical member, whose upper edge is rounded, as indicated at a.

B indicates the horizontal member, extending from the lower edge of the member A, said horizontal portion B having an upwardly-extending flange C at its outer extremity and an upwardly-extending rib D on its upper face between flange C and the member A. 30

The vertical and horizontal members, together with the ribs on the horizontal member, run parallel with each other, and the vertical member A is perforated by a series of openings a', arranged therein as shown. 40

What I claim is—

The design for a car-door track, substantially as herein shown and described.

In testimony whereof I hereunto affix my signature, in the presence of two witnesses, 45 this 1st day of April, 1898.

EDWARD S. MARSHALL.

Witnesses:

F. R. CORNWALL,
HUGH K. WAGNER.
